UNITED STATES PATENT OFFICE.

GUSTAF A. LINDSTROM AND GEORGE SENN, OF GREEN BAY, WISCONSIN.

EXERCISER.

Application filed January 11, 1921, Serial No. 436,538. Renewed March 18, 1922. Serial No. 544,956.

To all whom it may concern:

Be it known that we, GUSTAF A. LINDSTROM and GEORGE SENN, citizens of the United States, and residents of Green Bay, in the county of Brown and State of Wisconsin, have invented certain new and useful Improvements in Exercisers, of which the following is a specification.

Our invention is an improvement in exercisers, and has for its object to provide a device of the character specified, which may be connected to the top of an ordinary door-way, without marring the finish of the frame of the door-way, and which when so connected, will provide a horizontal bar firmly held in place and capable of supporting any reasonable weight that may be put upon it.

In the drawings:

20 Figure 1 is a front view of the improved exerciser in place,

Figure 2 is a longitudinal vertical section through the exerciser,

25 Figure 3 is a vertical section through the door frame showing the device adapted to suspend a swing,

Figure 4 is an enlarged transverse section through the casing and exerciser,

30 Figure 5 is a perspective view of one of the clamping sections looking from within,

Figure 6 is a side view of the same,

Figure 7 is a perspective view of one of the abutment sections,

35 Figure 8 is a similar view of the other section.

In the present embodiment of the invention, there is provided a bar, a hanger for the bar, and a pair of abutments for the ends of the bar. The bar is a rod 1, having 40 arranged thereon sleeves 2, the sleeves fitting smoothly upon the rod, and being spaced apart at their adjacent ends by the hanger.

The hanger as shown more particularly in 45 Figure 4 consists of a substantially U-shaped member or yoke composed of a body 3 and arms 4, both body and arms being T-shaped in cross section, and at the center of the body there is provided a transverse opening 50 for receiving the rod 2. The ends of the sleeve abut the web of the body and each of the arms 4 has a bearing 5 at its free end. One of these bearings holds a pin 6, and through the other a screw 7 is threaded, 55 the inner ends of the pin and screw being pointed, while the outer end of the screw

has a cross head as shown for facilitating the turning of the same.

There is provided, in the ordinary construction of door-ways, a transverse stud 60 or cross beam 8 at the top of the casing, the said beam connecting the side members 9 of the casing. This beam is faced by strips 10 on its underface and at its side, and molding 11 is arranged at the top of the 65 side faces.

A pair of clamping members indicated at 12 is connected with the top of the casing, each of the said hangers being a plate having its upper end bent to form a hook 13 which 70 will engage above the molding as clearly shown in Figures 3 and 4. The inner face of each of these plates 12 is faced with a strip 14 of soft material, as for instance, felt or the like, to prevent abrasion of the facing 75 or the molding. The bill of the hook 13 extends substantially perpendicular to the body of the plate, and this hook engages above the molding, as shown, the body of the hook fitting against the side facings 10. 80

The outer face of the plate 12 is provided with a vertically arranged series of openings 15, and each of these openings is shaped to fit the ends of the pin 6 or the ends of the screw 7. In order to connect the hanger, 85 the clamping plates are placed on each side of the casing and top, with the hooks engaging over the molding and the top of the facing. The yoke is now placed as shown in Figure 4, the screw being loosened to permit 90 the pin 6 to engage one of the openings 15 of the adjacent plate.

The screw 7 is now engaged with a corresponding opening of the other clamping plate, and the screw is tightened. The 95 tightening of the screw not only clamps the clamping plate on the casing, but also clamps the yoke on the plates. By engaging the screw and pin with different openings, the yoke may be adjusted vertically.

This hanger provides a support for the bar, but means is provided for preventing swinging of the same under a weight, the said means being in the form of abutments at each end of the taper. The abutments are 105 sectional, each consisting of an upper section 16 and a lower section 17. The upper section 16 of each abutment is an angle plate, having one portion adapted to fit against the underface of the cross member of the 110 casing, and a vertical portion depending therefrom. The upper face of the first

named portion is faced with a facing 18 of felt or the like.

The depending portion of the section has a slot 19, and the section 17 has an opening 20 adapted to register with the slot 19 to receive a bolt 21. This bolt is engaged by a wing nut 22 on the outer face of the depending portion of the section 16. By means of this bolt and nut, the sections may be adjusted with respect to each other, and referring to Figure 8, it will be seen that the opening 20 is polygonal to fit the bolt, but to prevent turning of the bolt when the nut is turned.

15 The section 17 also has an opening 23 for permitting the passage of the rod 1 of the bar, and nuts 24 are threaded onto the rod outside of the sections 17. By means of these nuts, the sections 17 may be tightly 20 clamped against the ends of the sleeves 2, the inner ends of the sleeves abutting the web of the yoke body.

The horizontal portions of the sections 16 abut the casing, and prevent any lateral 25 movement of the bar under stress. Each of the sections 17 is provided at its lower end with an opening 25, and these openings may be engaged by hooks 26 on flexible 30 members 27 which support at their lower ends a seat 28 providing a swing.

When it is desired to use the bar as a bar, for swinging exercises, the swing may be removed merely by unhooking the hooks 26. The entire structure may be easily 35 moved from the door, merely by loosening the screw 7. Thus the entire structure is held by the one screw.

We claim:

1. A device of the character specified, 40 comprising a bar and a hanger for the bar, said hanger consisting of a yoke having an opening through its body portion for the bar, one of the arms of the yoke having an inwardly extending pin, and a screw threaded 45 through the other arm, and clamping plates having hooks for engaging above the molding of a door casing and adapted to fit against the opposite faces thereof, said plates having openings in their outer faces 50 for engagement by the pin and screw, and abutments connected with the outer ends of the bar and abutting the underface of the top of the casing and adjustable in length, each of said abutments comprising sections, 55 one of which abuts the underface of the door casing and the other of which is connected with the bar, the bar comprising a rod passing through the opening of the yoke and connected with the abutments, and sleeves 60 encircling the rod between said abutments and the hanger.

2. A device of the character specified, 65 comprising a bar and a hanger for the bar, said hanger consisting of a yoke having an opening through its body portion for the

bar, one of the arms of the yoke having an inwardly extending pin, and a screw threaded through the other arm, and clamping plates having hooks for engaging above the molding of a door casing and adapted to fit against the opposite faces thereof, said plates having openings in their outer faces for engagement by the pin and screw, and abutments connected with the outer ends of the bar and abutting the underface of the top of the casing and adjustable in length, each of said abutments comprising sections, one of which abuts the underface of the door casing and the other of which is connected with the bar, said sections being adjustably connected.

3. A device of the character specified, comprising a bar and a hanger adapted to support the bar at its center, said hanger consisting of a yoke having a transverse opening through its body portion for the bar, one of the arms of the yoke having an inwardly extending pin, and a screw threaded through the other arm, and clamping plates having hooks for engaging above the molding of a door casing and adapted to fit against the opposite faces thereof, said plates having openings in their outer faces for engagement by the pin and screw, and sectional abutments connected with the outer 95 ends of the bar and abutting the underface of the top of the casing and coacting means carried by the sections whereby they may be adjusted with reference to each other.

4. A device of the character specified, comprising a bar and a hanger for the bar, said hanger consisting of a yoke having a transverse opening through its body portion for the bar adapted to support the bar at its center, one of the arms of the yoke having an inwardly extending pin, and a screw 105 threaded opening through the other arm, and clamping plates having hooks for engaging above the molding of a door casing and adapted to fit against the opposite faces thereof, said plates having a vertical series 110 of sockets in their outer faces for engagement by the pin and screw whereby the yoke may be vertically adjusted.

5. A device of the character specified, comprising a bar and a yoke hanger for the bar, adapted for connection with the cross member of a door frame to support the bar in spaced relation to the frame, and abutments for supporting the ends of the bar 120 and adapted to engage the said cross member to prevent swinging of the ends, said yoke hanger and abutments being sectional, the sections of the abutments being adjustable with respect to each other, and the sections of the yoke hanger also adjustable with respect to each other.

6. An exercising apparatus comprising a horizontal bar, an extensible hanger supporting the bar at its center, and adapted for 130

connection with the cross beam of a door frame, and extensible abutments or brackets supporting said bar at its ends and preventing swinging of the same, said abutments supported from the cross beam of the door frame.

7. An exercising apparatus comprising a horizontal bar, sleeves fitted on said bar at each side of its center and extending to adjacent its ends, an adjustable hanger adapted

frame, said hanger supporting said bar at its center between the inner ends of the said sleeves, adjustable abutments or brackets secured to the cross beam of the door frame and supporting the outer ends of said horizontal bar, the outer ends of the sleeves abutting said abutments and means cooperatively engaging the outer ends of the bar and the abutments to hold said bar in place.

GUSTAF A. LINDSTROM.
GEORGE SENN.
